[57] ABSTRACT

An ultrasound Doppler applicator is used for determining the movement of internal body parts the position of which is variable relatively to the applicator, particularly fetal heart movement. The invention is particularly characterized by the provision of a plurality of ultra sound sending oscillators and a plurality of ultra sound receiving oscillators carried by a ring and distributed over the entire ring.

ULTRASOUND DOPPLER APPLICATOR

This invention relates to an ultrasound Doppler applicator determining the movement of internal body parts the position of which is variable relatively to the applicator, particularly fetal heart movement.

Known applicators of this type are used for determining fetal heart movements. The simplest applicator consists of two oscillators located close to each other, one of which functions as a sender and the other as a receiver. Such an applicator has a comparatively sharp sending-receiving directional characteristic and is therefore not well suited for continuous supervision of fetal heart movement, since by movement of the fetus its heart can easily leave the range of the sound. Furthermore, the signal output is comparatively small, since the receiving oscillator actually gets only echo signals from reflection surfaces perpendicular to the flow direction of the sound.

Another known applicator has a flat disc serving as a carrier for several receiving oscillators arranged in a concentric circle about a central sending oscillator. This applicator makes possible the coverage of the entire possible movement range of the fetus and it also produces a higher signal output since the receiving oscillators grouped around the sending oscillator also register echo signals from surfaces with a certain inclination. However, there are difficulties in coupling the individual oscillators to the body surface of the person, since the flat, rigid disc with comparatively large surface is difficult to adapt to a body surface with different curvatures.

An object of the present invention is to provide an applicator which will also cover the entire movement range of the fetus but, as compared to prior art, will have a greater increase in signal output and at the same time can be coupled in a much simpler and safer manner to very curved body surfaces.

Other objects of the present invention will become apparent in the course of the following specification.

In the accomplishment of the objectives of the present invention it was found desirable to provide a ring carrying a plurality of ultra sound sending oscillators and a plurality of ultra sound receiving oscillators, the oscillators being distributed over the entire ring.

A ring can be much better adapted to curved soft surfaces than a disc. The increased adaptability of the oscillator carrier provides a better and less critical coupling of the individual oscillators to the curved body surface. Furthermore, a plurality of ultra sound sending oscillators located outside of the application center provide a much better space illumination of the object being examined (fetus hearts), with the result that the signal output will be further increased by a substantial amount.

According to an advantageous embodiment of the present invention the individual sending oscillators and receiving oscillators are arranged alternately upon the ring in a circle which is concentrical to the center of the ring. The distances between the oscillators are made equal.

According to a particularly effective embodiment of the present invention a total of three sending oscillators and three receiving oscillators, each having a diameter of about 8 mm, is mounted upon a ring having an average diameter of about 50 mm. Such an applicator provides best receiving conditions for echo signals from a

depth range of about 6 cm to 12 cm, namely, specifically for echo signals coming from the heart of the fetus (average distance of fetus from body surface is about 8 cm).

According to a further advantageous development of the present invention there is also provided a pressure changer, for example, a pressure balloon, fitting into the interior of the ring, for simultaneously receiving the tocogram of the circular ends. The ring can be the member receiving the pressure changer or it can be a component part of the casing of the pressure changer.

The invention will appear more clearly from the following detailed description when taken in connection with the accompanying drawing showing by way of example only, preferred embodiments of the inventive idea.

In the drawing:

FIG. 1 is a front view of an ultrasound Doppler applicator.

FIG. 1a is a section along the line A — A of FIG. 1.

FIG. 2 is a front view of an applicator combined in a tocogram receiver.

FIG. 2a is a section along the line B — B of FIG. 2.

The ultrasound Doppler applicator for determining fetal heart movements shown from the application side in FIG. 1, includes a total of three ultrasound sending oscillators 1, 2 and 3 and three receiving oscillators 4, 5 and 6 consisting of piezoelectrical crystal plates with a diameter of about 8 mm. The oscillators are arranged as an alternating row upon a carrier member 7 having hollow spaces 7' for receiving the oscillators. The carrier member 7 has an application surface 8 and a cover 9 which can be screwed on. Thus these parts form a ring 10 made of polystyrol. The average diameter of the ring 10 amounts to 50 mm, its width is 9 mm and its total thickness is 10 mm.

The individual sending and receiving oscillators are electrically connected in parallel and work in continuous stroke or impulse operation. Electrical conduits 11 and 12 are connecting lines of the individual sending oscillators or receiving oscillators with sending high frequency generator or Doppler device for indicating Doppler signals (both not shown).

An applicator combined with a tocogram receiver 13 is shown again from the application side in FIG. 2.

The tocogram receiver 13 consists of a pressure balloon 14 inserted into the round interior of the disc 10 and having a rigid casing part 15 and a balloon membrane 16. The balloon 14 can be blown up by a pump (not shown) connected to a pressure conduit 17 to a desired volume or pressure value. The conduit 17 also carries a mechanical-electrical pressure changer (not shown) for changing pressure variations in the balloon 14 into corresponding electrical signals (tocogram).

The described ultrasound Doppler applicator is used as follows:

The ring 10 is applied, for example, by means of an adhesive plaster to the stomach in such manner that the individual sending and receiving oscillators are in good contact with the skin. The ultrasound waves emitted by the senders 1 to 3 are among others, reflected by the fetus heart and the reflected waves are transformed in the receiving oscillators 4 to 6 into corresponding electrical signals. The frequency deviations resulting from

heart movements between the sent out ultra sound and the received ultra sound produce Doppler signals constituting a measure for the heart movements of the fetus. The heart frequency of the fetus can be determined directly from the following frequency of the appearing Doppler signals.

According to FIGS. 2 and 2a to the heart movements of the fetus is also added the tocogram, namely the contraction signal of the woman. For that purpose the balloon 14 blown to a specific volume or pressure value, is pressed into the interior of the ring so that the diaphragm 16 presses against the stomach of the woman.

If uterus contractions take place, they are received as pressure variations in the balloon 14 and are transmitted by the pressure conduit 17 to the mechanical-electrical pressure changer.

What is claimed is:

1. An ultrasound Doppler applicator for determining the movements of internal body parts the locations of which are moveable relatively to the applicator, particularly fetal heart movements, said applicator comprising a ring and a plurality of ultrasound sending oscillators and ultrasound receiving oscillators carried by said ring, said oscillators being distributed throughout the entire ring.
2. An applicator in accordance with claim 1, wherein the individual sending and receiving oscillators are mounted alternately upon said ring along a circle concentric to the center of said ring.
3. An applicator in accordance with claim 2, wherein

the distances between the applicators are equal.

4. An applicator in accordance with claim 3, wherein there are three sending oscillators and three receiving oscillators, each oscillator having a diameter of substantially 8 mm, said ring having an average diameter of substantially 50 mm.

5. An applicator in accordance with claim 4, wherein the width of said ring is substantially 10 mm.

6. An applicator in accordance with claim 1, wherein said ring comprises hollow spaces receiving said oscillators.

7. An applicator in accordance with claim 1, comprising means connecting the individual sending oscillators and receiving oscillators electrically in parallel.

15 8. An applicator in accordance with claim 1, wherein said ring consists of an artificial material, preferably polystyrol.

9. An applicator in accordance with claim 1, wherein said ring is a disc ring.

20 10. An applicator in accordance with claim 1, comprising a pressure changer fitting into the interior of said ring for receiving a tocogram of an expectant mother.

11. An applicator in accordance with claim 10, wherein said ring encloses and holds said pressure changer.

25 12. An applicator in accordance with claim 10, wherein said pressure changer has a casing, said ring being a part of said casing.
